[57] CLAIM

The ornamental design for a mobile for display advertisements or the like, thereof.

DESCRIPTION

FIG. 1 is a top perspective view of a mobile for display advertisements or the like showing my new design; FIG. 2 is a top plan view of FIG. 1 in blank form, the undisclosed rear being a mirror image;

FIG. 3 is a side elevational view of FIG. 1, it being understood from FIG. 2 that the undisclosed side is flat and plain;

FIG. 4 is a front elevational view thereof, it being understood from FIG. 2 that the undisclosed rear is flat and plain; and

FIG. 5 is a bottom plan view thereof.

FIG. 1

FIG. 2

FIG. 3

FIG. 4

FIG. 5
